G. H. Corporon
INVENTOR
BY Victor J. Evans.
ATTORNEY

UNITED STATES PATENT OFFICE.

GAINES H. CORPORON, OF CITRUSGROVE, TEXAS.

PROPELLER.

Application filed November 2, 1920, Serial No. 421,328. Renewed June 1, 1923.

To all whom it may concern:

Be it known that I, GAINES H. CORPORON, a citizen of the United States, residing at Citrusgrove, in the county of Matagorda 5 and State of Texas, have invented new and useful Improvements in Propellers, of which the following is a specification.

This invention comprehends the provision of a compound propeller for aero-planes or 10 the like, with a view of increasing the efficiency of the horse power of the motor, to practically eliminate the gyroscopic effect of a single propeller.

The nature and advantages of the invention 15 will be better understood when the following detail description is read in connection with the accompanying, the invention residing in the construction, combination and arrangement of parts as claimed.

20 In the drawing forming part of this application like numerals of reference indicate similar parts in the several views and wherein:

Figure 1 is a fragmentary view of a motor 25 showing the propeller mechanism in section.

Figure 2 is a sectional view taken on line 2-2 of Figure 1.

Referring to the drawing in detail 10 indicates the base of the motor and 11 the 30 crank shaft which projects an appreciable distance beyond one end of the base as shown. The base 10 of the motor is recessed as at 12 to accommodate the large beveled gear 13 which is keyed or otherwise 35 suitably secured to the crank shaft 11. A similar gear 14 is arranged in confronting relation to the gear 13, and is keyed or otherwise suitably secured to a sleeve 15 which receives the crank shaft 11. Interposed between the gears 13 and 14 is a spider 40 preferably having four points or ends 16, each limb accommodating a pinion gear 17 which meshes with both of the gears 13 and 14. The foremost propeller 18 is directly

mounted or associated with the crank shaft 45 11 and rotates to the right with the crank shaft, while the rear propeller 19 is carried by the sleeve 15 and rotates in an opposite direction through the gearing arrangement as will be readily understood. Mounted upon 50 the sleeve 15 is a casing or cover 20 for the gears 14 and 17, this casing having a hub like portion 21 surrounding the sleeve 15, while the portion of the covering or casing is recessed as at 22 to receive the gear 14 55 and a portion of the gears 17. The cover or casing 20 is secured to the motor base 10 in any suitable manner as at 23, while the limbs 16 of the spider project beyond the pinion gears 17 and are clamped between 60 the motor base 10 and the cover 20.

While it is believed that from the foregoing description the nature and advantages of the invention will be readily apparent, I desire to have it understood that I do not 65 limit myself to what is herein shown and described and that such changes may be resorted to when desired as fall within the scope of what is claimed.

What I claim is:

In combination with a motor and crank shaft therefor, of a propeller carried by the crank shaft, a sleeve receiving said crank shaft, a second propeller mounted on the sleeve, beveled gears secured to the crank 75 shaft and sleeve respectively, a spider interposed between the gears, pinion gears carried by the limbs of the spider and connecting with the aforementioned beveled gears, a cover for certain of said gears including a 80 hub portion surrounding said sleeve, and a body portion having a recess to receive the said gears, means for securing the body of the cover to the base of the motor, and said limbs of the spider being clamped between 85 the base and said cover as described.

In testimony whereof I affix my signature.

GAINES H. CORPORON.
